ELECTRICAL APPARATUS

Harry F. Smith, Dayton, Ohio, assignor to General Motors Corporation, Dayton, Ohio, a corporation of Delaware

Application May 26, 1934, Serial No. 727,774

4 Claims. (Cl. 156—15)

This invention relates to electrical apparatus and more particularly to the actuation of awnings, shades or other light transmission modifiers for window or door openings automatically 5 and manually.

An object of this invention is to provide control devices for the fixtures associated with the windows, doors or other openings of edifices in such a manner that they may be controlled with 10 but slight manual effort or automatically in accordance with various environmental conditions.

Further objects and advantages of the present invention will be apparent from the following description, reference being had to the accompanying drawings wherein a preferred form of 15 the present invention is clearly shown.

In the drawings:

Fig. 1 is a diagrammatic representation, partly in section and partly in perspective, of a portion of an edifice embodying features of my invention;

Fig. 2 is a plan view of the motor structure now preferred for use in actuating the awnings or other light transmission modifiers.

Fig. 3 is a vertical elevational view of Fig. 2; Fig. 3a is an enlarged cross sectional view of a portion of Fig. 3;

Fig. 4 is a wiring diagram of the electrical control for the awning structure shown in Fig. 1.

My invention is particularly applicable to an edifice such as a house, office building or the like, which is provided with one or more openings or windows of the character shown in Fig. 1, which is representative of a plurality of such 35 openings or windows throughout the edifice. This window, door or the like is provided with one or more sash openings 10, each having a closure 11 in the form of a window sash or the like and an awning, shade or light transmission 40 modifier 12 which may overhang one or more of the sash openings 10 on the outside of the building. Actuating means and control means, hereafter more fully described, are provided for actuating the closures 11 and modifiers 12, not 45 only under manual control, but also automatically in accordance with selected environmental conditions such as light intensity, rainfall or any other environmental condition.

The actuation of the awning, shade or light 50 transmission modifier 12 now will be more fully described. The awning 12 which is pivotally secured to the building in the usual manner, may be raised or lowered by means of a cable 13 passing over a pulley 14 and attached to the 55 lower or outer end of the awning at 15. This

cable passes over a pulley 16 and winds around the drum 17 which is actuated by the motor 18 under a manual control at 19 and 20 and under an automatic environmental control 21. The awning is so controlled that it automatically 5 rises, for example, when the sunlight diminishes below a certain intensity and automatically lowers when the sunlight increases above a certain intensity. This is accomplished by providing a photoelectric cell 22 which is responsive to 10 such sunlight intensities, and which initiates impulses which are relayed eventually to the one or more motors 18 to actuate properly the awning or awnings 12. The electrical impulses initiated at the cell 22 flow to a current intensifying aggregate 23 from whence the current thus 15 intensified flows to a master switch structure 24 which relays a governing current to the various individual relays 25, placed throughout the edifice, for each window of the edifice. Each relay 20 25 controls the flow of standard or city power current to its individual motor 18.

The wiring diagram for this control is shown more in detail in Fig. 4, where the photoelectric cell is shown at 22, the wiring structure within 25 the intensifying aggregate is shown within the dotted line 23, the wiring within the motor switch structure 24 is shown within the dotted line 24 and the relay 25 is indicated in two enclosures 25a and 25b of Fig. 4, 25b indicating 30 the wiring from the city current to the motor 18 and 25a indicating the wiring from the aggregate 24 to the relay solenoids. When sunlight of proper intensity falls on the cell 22, a slight current is caused to flow through the solenoid 35 30 of the swinging galvanometer 31 and, depending on the intensity, the arm 32 swings either to the right or to the left. Therefore, when the sunlight falls below a predetermined limit, the current flowing through the solenoid 30 decreases to such an extent that the arm 32 40 swings to the right and closes the contacts 33. This causes the current to flow from the battery 34 through an electric heater for the bimetallic switch 35, closing the contacts 36. This causes 45 the current to flow through the solenoid 37 of the switch 38 and closes the contacts 39. At the same time a complementary switch 40 is de-energized so that the contacts 41 are closed under spring tension and this permits a current 50 to flow from the battery 34 through the solenoid 42 and through the contact 43 back to battery 34. When the solenoid 42 is energized, the lever 44 releases the contact arm 45 and closes the contacts 46. This in turn permits 55

current to flow from the battery 47 to the motor 48 which turns, through gear reduction, the switch arms 49 and 50 and the cam 51. The arm 49, when it turns, comes in contact with contacts 52 and 53 alternately and energizes the solenoids 54 and 55 of the relay 25 which in turn control the flow of current to the motor 18 and determine the direction of rotation of the motor 18. The arrangement is such that 5 contacts 52 and 53 alternately and energizes the solenoids 54 and 55 of the relay 25 which in turn control the flow of current to the motor 18 and determine the direction of rotation of the motor 18. The arrangement is such that 10 when the cell 22 has caused an impulse to travel through contacts 33 it cannot reverse the chain of actuations until such chain has been completed and has caused the awning to rise to its final position. Thereafter if the sunlight has 15 intensified sufficiently, and the arm 32 contacts at 60, the awning will be lowered. This is accomplished by causing current to flow through the heater of the bimetallic switch 61 which closes the contacts 62 (after the contacts 36 20 have been opened by cooling) so that current now flows to the solenoid 63, causing current to flow through the contacts 64 and 65, thus again causing current to flow through the solenoid 42 and through the complementary contact 66 to again release the lever 45 and cause the motor 48 to turn the arms 50 and 49 and cam 51 another 180°. This causes the relay 25 to actuate the motor 18 in the opposite direction, as will be further explained.

30 The arm 50 is caused to move from 43 to 66 when sunlight decreases. By this action further impulses from cell 22 due to decreased sunlight can not cause motor 48 to turn, and only an impulse due to increased sunlight can cause the motor 48 to turn. Therefore, the action of arm 50 is such that it only transmits the required impulses on to the motor 48 and to the awning 12.

35 The purpose of the bimetallic switches within the dotted circle 31a is to delay the impulses from the cell 22. This prevents the apparatus from being over sensitive to sunlight changes and causes it to transmit impulses only after the sunlight has remained above or below the desired limits of intensity for a certain length of time.

40 The movement of the arm 50 from 43 to 66 or from 66 to 43 may be made to require an even longer time than the heating and cooling of the switches in 31a. By this arrangement the cell 22 can not move the awning until the sunlight has retained the required intensity for a definite time due to the action of 31a. Also it can not reverse its impulse or command until the arm 50 45 has made its 180° travel. This 180° travel also is made to require a greater period of time than 50 the time required to raise or lower the awning.

45 In addition, manual controls are provided in the form of manual switches 70 and 71 which raise and lower the awning 12 by energizing the proper relays 54 and 55 which control motor 18 as will 55 be presently evident.

The motor 18 is so related to the cable 13 and to the relay 25 in such a manner that the tension of the cable 13 stops the motor when the awning is raised to its uppermost position or is 60 lowered to its lowermost position or meets an abnormal resistance such as by binding. To this end, the drum 17 on which the cable winds has 65 associated therewith a centrally pivoted spider 75 having arms 76, 77 and 78. The arm 76 is 70 provided with an idler pulley 79 which is responsive to the tension on the cable 13. When the awning reaches its topmost position, the cable is given a strong tension by the resistance of the awning and pull of the motor which moves 75 the spider in a counter-clockwise direction against

the compression of the spring 80, the pull of the cable being sufficient to overcome the resistance of spring 80 and causing the arm 77 to swing the pulley 81 against curved bridge 81a secured to the trip lever 82, thus releasing the resilient contact support or arm 83 so it may assume a neutral or central position as shown in Fig. 3. When the arm 83 is in this neutral position, no electrical energy can flow to the motor 18 and thus the motor actuation is stopped. When an impulse is given to lower the awning, the tension on the cable is reduced somewhat but is still sufficient to prevent the spring 84 from moving the arm 77 in a clockwise direction beyond the position shown in Fig. 2. However, when the awning reaches its lowermost position, substantially all of the tension on cable 13 is removed, and the arm 77 moves to its furthest clockwise position where it again acts on bridge 81a attached to a lever 82a, similar to the lever 82 which trips the carrier 83 and permits it to assume its neutral position.

To repeat briefly the operation of the awning control, the photoelectric cell 22 energizes or de-energizes the galvanometer 31. This in turn places 25 the switches 38 and 40 in position to energize the solenoid 42 and initiate a turning cycle of the motor 48 in the box or aggregate 24. The box 24 is provided with the motor 48 which drives the contact arms 49 and 50 and the cam 51 by proper 30 speed reducing gearing indicated by the line 48a. When an impulse is initiated at 22 and is relayed through to solenoid 42, the motor 48 is energized from battery 47 and continues to run until the arms 49 and 50 and cam 51 have completed a 35 half turn and the motor is stopped by the action of cam 51 on lever 45. When the motor 48 stops, the arm 50 is on either contact 43 or contact 66 and arm 49 is near either contact 52 or 53. Cam 51 depresses lever 45 cutting off current to motor 40 48 and locking arm 45 under lever 44. The coasting effect of motor 48 carries the cam 51 far enough to permit the contacts 46 to reclose if arm 45 is released by a subsequent impulse.

When the motor 48 causes arm 49 to make one 45 of its half turns, a current impulse is sent to either one of the solenoids 54 or 55 for a short period of time, the arm 83 being thus attracted either to the right or the left and being locked under either the lever 82 or 82a. This in turn 50 relays power current from the lines 85 and 86 through the proper ones of contacts 81-84 to the motor 18 which actuates the awning 12 up or down. The motor 18 continues to operate until the spider 75 trips the lever 82 or 82a and releases 55 the arm 83 to neutral position.

Thus an impulse from photoelectric cell 22 first energizes motor 48 which in turn energizes the motor 18. The motor 18 then runs until the cable tension trips the relay 25 at the top or bottom 60 limit of movement of awning 12.

In order to prevent the drum 17 from unwinding too far, the drum is provided with notches 95, and the rod 96 is provided with a lug 97. When the spring 84 is released by the cable tension, the 65 lug 97 moves into the path of the notches 95 and stops the drum.

Two springs 80 and 84 are provided to balance the different tensions of the cable 13 occurring when the awning is rising and when it is being lowered. When the awning is rising, the tension is greater than when it is being lowered. The spring 80 is therefore, in the one particular embodiment I have made, approximately a 25 pound spring and the spring 84 is a 5 pound spring. 70 75 75

The rod 96 is provided with a sleeve 98 threaded thereon together with a nut 99. Another sleeve 99a is slidably telescoped on sleeve 98 and is provided with a flange 99b adapted to receive the end of spring 80 and also to engage stop means 99c of the spring stop 99d mounted on motor 18. The tensions of the springs 80 and 84 may be adjusted by nuts 80a and 84a. By this construction the combined compression of the springs 80 and 84 is brought into play against the tension of the cable 13 while the awning is rising and yields when it reaches the top or binds. The spring 84 only is effective when the awning is lowered and it alone moves the spider past the central position to trip lever 82a when the awning reaches the bottom. This is because spring 80 can only act on the rod 96 when the sleeve 99a is against 99c, and this occurs only when spider 75 has turned slightly counter-clockwise beyond the central position.

Sometimes it is desirable to cause the awnings to stay down regardless of the sunlight intensity. One way of accomplishing this is to provide a lantern 150 which shines into cell 22 with sufficient intensity to lower the awnings. This lantern may be controlled from a switch 151 which has "on" and "off" buttons for lighting and darkening the lantern 150, as will be readily apparent.

While the form of embodiment of the invention as herein disclosed constitutes a preferred form, it is to be understood that other forms might be adapted, all coming within the scope of the claims which follow.

What is claimed is as follows:

- 5 1. In combination, an awning, a device initiating impulses in response to weather conditions, means to actuate said awning and governed by said impulses and means to neutralize the actuation of said awning under abnormal conditions. 10
- 10 2. In an edifice provided with a light opening, a light transmission modifier for said opening, means to actuate said modifier in accordance with light conditions and means to neutralize the 15 actuation under abnormal conditions.
- 15 3. In an edifice provided with an opening, a light modifier for said opening, a photo-electric cell responsive to sunlight conditions, and means controlling said light modifier by said photo-electric cell. 20
- 20 4. In an edifice provided with a light opening, a light transmission modifier for said opening, an electric motor to actuate said modifier in accordance with light conditions, and means to neutralize said motor under abnormal conditions. 25

HARRY F. SMITH.
